DESIGN FOR A COAT

Isidor Greenberg, University City, Mo., assignor
to Greenberg Garment Company, St. Louis,
Mo., a corporation of Missouri

Application June 13, 1936, Serial No. 63,286

Term of patent 3½ years

To all whom it may concern:

Be it known that I, Isidor Greenberg, a citizen of the United States, residing at University City, St. Louis County, Missouri, have invented a new, original, and ornamental Design for a Coat, of which the following is a specification, reference being had to the accompanying drawing, forming a part thereof, in which—

The characteristic feature of the design resides in the detachable collar of the proportions and configuration shown combined with the coat as shown.

I claim:

The ornamental design for a coat substantially as shown and described.

ISIDOR GREENBERG.
